UNITED STATES PATENT OFFICE.

ALFRED ANDERSON, OF EAST RUTHERFORD, NEW JERSEY, ASSIGNEE TO THE FLINT-KOTE COMPANY, OF BOSTON, MASSACHUSETTS, A CORPORATION OF MASSACHUSETTS.

SHEET-GUIDING DEVICE FOR SATURATING TANKS.

Application filed December 24, 1919. Serial No. 347,138.

To all whom it may concern:

Be it known that I, ALFRED ANDERSON, a citizen of the United States, residing at East Rutherford, in the county of Bergen and State of New Jersey, have invented new and useful Improvements in Sheet-Guiding Devices for Saturating Tanks, of which the following is a specification.

This invention has relation to apparatus for coating or impregnating fabric, such, for example, as for impregnating paper felt with a waterproofing compound in the manufacture of prepared roofing.

In the production of such roofing, the sheet of paper felt is drawn through a tank containing asphalt or other suitable bituminous or resinous compound, in a molten and liquid condition, so that the sheet will absorb the molten material in its pores or interstices. Such paper felt varies in porosity and absorbent characteristics according to the materials of which it is made and other conditions surrounding its manufacture, and consequently the length of time in which it is immersed in the impregnating compound must vary with its porosity or powers of absorption. Likewise the period of immersion frequently depends upon the viscosity of the saturant. While it is therefore highly desirable to vary the period in which the fabric is immersed in the saturating compound, it is not desirable that this should be accomplished by greatly varying the speed at which the fabric travels through the saturating tank. It will be readily understood that, where the speed of travel is decreased, a decrease in production follows as a logical result, and moreover it frequently causes the slowing down of the other instrumentalities which operate on or in connection with the saturated sheet. Roofing felt, because of the necessity of having it highly porous and absorbent, possesses relatively little tensile strength, and it occasionally happens that the sheet parts or is broken while in or before passing through the saturating tank, thereby requiring the sheet to be threaded through or around the various guides which guide it during its submergence in the compound. Where such materials as molten asphalt, heated to a high temperature, are employed, the operation of threading or passing the sheet through

or around the guides is a dangerous one for the operatives.

The present invention consists of a saturating tank having improved guiding means for guiding the traveling fabric or sheet through the saturating compound, so constructed that the guides may be moved to a point above the level of the saturant to permit the sheet to be engaged therewith, and then submerged in the saturant so as to carry the sheet thereinto. The guiding means, likewise, are so constructed and arranged that the period of immersion of the sheet in the saturant may be varied.

On the accompanying drawings,—

Figure 1 illustrates in side elevation a saturating tank provided with sheet-guiding means embodying the present improvement.

Figure 2 represents a section on the line 2—2 of Figure 1.

Figure 3 represents a section on the line 3—3 of Figure 1.

Figure 4 represents a transverse vertical section on the line 4—4 of Figure 1.

I have not illustrated the roll from which the sheet of felt is drawn nor the feeding means by which the sheet is caused to travel through the bath of molten saturant, as these are well known. It will be understood, however, that the sheet is preferably caused to travel at a uniform rate of speed by devices which may be stopped and started at the will of the operator, though the speed may be varied if desired.

On the drawings, a tank 10 is illustrated for containing a body of molten asphalt, bitumen or other waterproofing compound. Usually means (not shown) are employed for maintaining the saturant at the desired temperature and at the desired degree of viscosity. At one end of the tank is shown a guide roll 11 journaled in brackets 12, over which the sheet passes from the roll of raw felt. Squeeze rolls 13, 13, at the other end of the tank are shown as mounted in a bracket 14. The sheet of felt or other material to be saturated is indicated at 15. For the purpose of causing the sheet to travel through the bath of saturating compound, I employ guides which are mounted in a rotatable frame. These guides may take the form of rods, but I have illus-

trated them as rolls 16, 17 and 18 which are respectively journaled on shafts or rods 19, 20 and 21. The frame, in which said rods are mounted, consists of end bars 22, which 5 intermediate of their ends are rigidly secured to a shaft 23. The guide 18 is mounted in one end of each of said bars and guides 16 and 17 are mounted in the other ends of said bars, so that the guide 18 and the guides 10 16 and 17 are practically diametrically opposite each other. The frame is mounted so that it may be moved bodily vertically and also so that it may be partially rotated in one direction or the other. The shaft 23 is journaled in a carrier comprising two vertical slides 24 which are operatively engaged with two upright guides 25. The guides are provided or formed with rack teeth, as indicated at 26, and in the upper ends of the 15 slides there is journaled a shaft 27 having pinions 28 thereon intermeshing with the rack teeth. A hand wheel 29 on the shaft 27 affords means for rotating the shaft, and, by the engagement of the pinions with the 20 upright racks, causing the carrier and the frame thereon to be raised or lowered as the case may be. Assuming that the rotatable guide frame is in the position seen 25 in Figure 1, it is quite apparent that with 30 ease the sheet 15 of felt may be passed under the guide 18 and between the guides 16 and 17, and thence to the squeeze rolls. Thereupon the carrier may be depressed so as to carry the guides down to a point 35 where the fabric will be immersed in the saturating compound.

It is desirable, as previously stated, that the period of immersion of the fabric in the saturant, or the length of fabric that 40 at any one time is immersed in the saturant may be increased. This is accomplished by rotating the guide frame in the direction of the arrows in Figure 1 so that the fabric will be looped about the guides and caused 45 to pass back and forth while submerged. By rotating the guide frame through an arc of 180°, the guides may be so positioned that the sheet, after leaving the roll 11, will pass under the guide 17, thence around 50 guide 18, and then under and over the guide 16 to the squeeze rolls. By rotating the frame through an arc of less than 180°, the length of fabric undergoing immersion may be decreased. It is unnecessary with 55 this construction to adjust the guides relatively, their relation to the sheet controlling the time of saturation.

For the purpose of effecting the rotation of the guide frame, the following mechanism 60 may be employed, namely a shaft 30 journaled in the slides 24 and having sprocket wheels 31 for transmitting power by endless chains 32 to sprocket wheels 33 on the shaft 23. A hand wheel 34 may be utilized 65 for rotating the shaft 30.

The slides may be clamped in any position to which they may be adjusted by any suitable form of clamping mechanism. For example, as shown in Figures 2 and 3, the guides may be provided with webs 35, 70 36, which embrace the upright racks 25 and which may be clamped together by clamping screws 37. These screws are illustrated as passing through blocks 38 which bear against the faces of the upright guides opposite the toothed faces thereof. 75

In threading the sheet of fabric through the machine, the guide frame may be elevated to the position shown in full lines in Figure 1 and the sheet engaged with the 80 guides in the manner previously described. The guide frame may then be lowered below the level of the saturant, which is indicated by the dotted line *a a*, or the frame may first be rotated partially before it is depressed to submerge the sheet in the saturant. 85

Having thus explained the nature of my said invention and described a way of making and using the same, although without 90 attempting to set forth all of the forms in which it may be made or all of the modes of its use, what I claim is:

1. Sheet-treating apparatus comprising a tank for containing a body of liquid saturating compound, guides for a traveling sheet to guide the sheet through the saturating compound, and the means for varying the guiding relation of the guides to the sheet while maintaining said guides relatively 100 fixed to vary the length of the sheet undergoing immersion. 95

2. Sheet-treating apparatus, comprising a tank for containing a body of liquid saturating compound, spaced guides for a traveling sheet to guide the sheet through the saturating compound, a frame in which said guides are mounted, and means for bodily rotating said frame to vary the length of the sheet undergoing immersion. 105

3. Sheet-treating apparatus, comprising a tank for containing a body of liquid saturating compound, spaced guides for a traveling sheet to guide the sheet through the saturating compound, a frame in which said guides are mounted, means for bodily moving said frame to expose said guides above the level of the saturating compound, and means for bodily rotating said frame to vary the length of the sheet undergoing immersion. 115

4. Sheet-treating mechanism, comprising a tank for containing a body of liquid saturating compound, parallel guides for a traveling sheet to guide said sheet through the 125 saturating compound, and means for partially revolving said guides to form loops in the sheet.

5. Sheet-treating mechanism, comprising a tank for containing a body of liquid satu- 130

rating compound, a shaft, arms secured on said shaft intermediate of their ends, guides for a travelling sheet mounted in the opposite ends of said arms, and means for rotating said shaft to cause said guides to form loops in said sheet.

6. Sheet-treating mechanism, comprising a tank for containing a body of liquid saturating compound, a shaft, arms secured on 10 said shaft intermediate of their ends, guides for a travelling sheet mounted in the opposite ends of said arms, means for rotating said shaft to cause said guides to form loops in said sheet, and means for bodily raising 15 and lowering said shaft.

7. Sheet-treating mechanism, comprising a tank for containing a body of liquid saturating compound, a shaft, arms secured on 20 said shaft intermediate of their ends, guides for a travelling sheet mounted in the opposite ends of said arms, means for rotating said shaft to cause said guides to form loops in said sheet, a carrier for said shaft, and means for moving said carrier up and down 25 in reference to said tank.

8. Sheet-treating mechanism, comprising a tank for containing a body of liquid saturating compound, a shaft, arms secured on 30 said shaft intermediate of their ends, guides for a travelling sheet mounted in the opposite ends of said arms, means for rotating said shaft to cause said guides to form loops in said sheet, a carrier for said shaft, up- 35 right guideways for said carrier, and rack-and-pinion mechanism for moving said carrier on said guideways.

9. Sheet-treating mechanism, comprising a tank for containing a liquid saturating

compound, a rotatable frame, a shaft for supporting and rotating said frame, a guide 40 on said frame on one side of said shaft, a pair of guides on said frame on the other side of said shaft, said guides being adapted to guide a sheet through the saturating compound, and means for partially rotating said 45 shaft whereby said guides form loops in the sheet.

10. Sheet-treating mechanism, comprising a tank for containing a liquid saturating compound, a rotatable frame, a shaft for 50 supporting and rotating said frame, a guide on said frame on one side of said shaft, a pair of guides on said frame on the other side of said shaft, said guides being adapted to guide a sheet through the saturating compound, means for partially rotating said 55 shaft whereby said guides form loops in the sheet, and mechanism for bodily moving said frame and guides vertically to immerse them in or withdraw them from the compound in 60 the tank.

11. Sheet-treating apparatus comprising a tank for containing a body of liquid saturating compound, spaced guides for a travelling sheet to guide the sheet through the saturating compound, a frame on which said guides are mounted, and means for moving said frame to vary the effective guiding relation of said guides to said sheet while they remain fixed relative to each other to thereby 65 vary the length of the sheet undergoing 70 immersion.

In testimony whereof I have affixed my signature.

ALFRED ANDERSON.
